CLAIM

The ornamental design for a computer mouse, as shown and described.

DESCRIPTION

FIG. 1 is a top, right-side, and front view of a computer mouse, showing the new design.

FIG. 2 is a front elevation view of the computer mouse.

FIG. 3 is a top plan view of the computer mouse.

FIG. 4 is a rear elevation view of the computer mouse.

FIG. 5 is a right-side elevation view of the computer mouse.

FIG. 6 is a bottom plan view of the computer mouse; and, FIG. 7 is a left elevation view.

The broken line elements represent unclaimed parts of the computer mouse, and form no part of the claimed design.
